UNITED STATES PATENT OFFICE.

WARREN W. STOLER, OF DETROIT, MICHIGAN, ASSIGNOR TO AMERICAN FORGING & SOCKET CO., OF DETROIT, MICHIGAN, A CORPORATION OF MICHIGAN.

TUBE-FORMING MACHINE.

1,191,362.

Specification of Letters Patent. Patented July 18, 1916.

Application filed May 20, 1915. Serial No. 29,402.

To all whom it may concern:

Be it known that I, WARREN W. STOLER, a citizen of the United States of America, residing at Detroit, in the county of Wayne 5 and State of Michigan, have invented certain new and useful Improvements in Tube-Forming Machines, of which the following is a specification, reference being had thereto in the accompanying drawings.

10 In the automobile industry, vehicle tops are made having wooden bows with the ends thereof provided with sockets and the greater part of said sockets is formed of tapering tubes or casings. It is the manufacture of these tapering tubes or bow sockets to which my invention relates.

First, my invention aims to provide a novel machine wherein positive and reliable means are employed, in a manner as herein-after set forth, for expeditiously and economically producing tapered tubes, light in weight and possessing sufficient rigidity to coöperate with a wooden frame in providing a rigid and durable bow.

25 Second, my invention aims to provide a machine wherein a tapering flanged blank or piece of skelp can be successively operated upon to shape the blank into a tapering tube having a closed seam within the 30 periphery of the tube.

Third, my invention aims to provide a bow socket forming machine wherein the parts are constructed with a view of reducing the cost of manufacture and at the 35 same time retain the features by which accuracy, simplicity and ease of fabrication are secured.

The principal elements of my invention—namely, a main frame, bed plate and dies; 40 a vertically reciprocable mandrel, its support and operating mechanism; a mandrel follower and its operating mechanism; tube overlapping members and their actuating means; a tube ejector and its operating mechanism, the controlling mechanism of the machine and the operation of producing a tube—will be hereinafter separately and specifically described in detail, together with the novel arrangement and objects accomplished from such a combination of elements.

In the drawings, Figure 1 is a side elevation of the machine, partly broken away

and partly in section; Fig. 2 is a view of one end of the machine; Fig. 3 is a cross sectional view of the machine taken on or about the line III—III of Fig. 1; Fig. 4 is a horizontal sectional view of a portion of the machine, taken on or about the line IV—IV of Fig. 1; Fig. 5 is a longitudinal, 60 vertical sectional view taken on or about the line V—V of Fig. 4; Fig. 6 is a view of the opposite end of the machine from that shown in Fig. 2; Fig. 7 is an enlarged longitudinal sectional view of a portion of the 65 machine, illustrating the tube ejector; Fig. 8 is a plan of a portion of a blank from which a tube is formed; Fig. 9 is an end view of the same; Fig. 10 is an enlarged cross sectional view of a mandrel; Fig. 11 70 is a perspective view of the same; Fig. 12 is a similar view of a tapering tube formed by the machine; Fig. 13 is an enlarged cross sectional view of the same; Fig. 14 is a cross sectional view of a portion of 75 the machine, illustrating a blank in position preparatory to being formed; Fig. 15 is a similar view illustrating the action of a mandrel and mandrel follower; Fig. 16 is a similar view illustrating the action of 80 coöoperating members adapted for overlapping edges of the blank; Fig. 17 is a similar view illustrating the action of the mandrel follower for closing the seam of a tube, and Fig. 18 is a perspective view of a portion of one of the dies of the machine.

In describing my invention by aid of the views above referred to, I desire to point out that the same are merely illustrative of the machine as actually built, and that 90 I do not care to confine my invention to the precise construction and arrangement of parts shown. The following description is therefore to be broadly construed as including substitute constructions and arrangement of parts which are obvious equivalents to those to be hereinafter referred to.

Main frame, bed plate and dies, (Figs. 1 to 6 inclusive.)—In the drawings, 1 and 2 denote end frames connected by a tie rod 3 100 and a bed plate 4. On the end of the bed plate 4 are vertical guides 5 and 6 and longitudinally of said bed plate are parallel walls 7 having the upper edges thereof bevelled or inclined inwardly. See Fig. 3. Between the walls 7 are dies 8 and 9 held

against vertical displacement by bolts 10 extending through slots 11 provided therefor in the bed plate 4. The dies 8 and 9 are yieldably held in a horizontal plane by a plurality of coiled compression springs 12 arranged in sockets or recesses 13 provided therefor in the outer walls of said dies, and said springs are held under tension by screw bolts 14 adjustable in the walls 7 of the bed plate 4. The dies 8 and 9 have the upper faces thereof provided with transverse grooves 15 for adjustable retaining members 16 adapted to prevent lateral displacement of a blank placed upon said dies. Either one of the dies, preferably the die 8, has a series of openings or sockets 17 for detachable retaining pins 18 adapted to prevent longitudinal displacement of a blank upon said die. The retaining members and pins can be easily adjusted to properly position blanks of various widths and lengths, and by reference to Figs. 8 and 9, it will be observed that the blank, as designated 19, is flat and has tapering flanged edges, the taper of the blank being from one end thereof to the opposite end and a hook shaped flange 20 at one side of the blank and a similarly shaped flange 21 at the opposite side thereof. This blank can be easily placed upon the dies 8 and 9 and held by the retaining members and pins preparatory to receiving its initial formation. Between the dies 8 and 9 is a beveled raised portion 22 and detachably connected thereto by screws 23 or other fastening means is a liner 24 constituting a bottom die which co-operates with the confronting walls of the dies 8 and 9 in holding the blank 19 during its initial formation.

Mandrel, its support and operating mechanism, (Figs. 1, 5, 6, 7 and 11.)—The guide 6 has a rectangular opening 25 and connected to the outer side of said guide, at the sides of the opening 25, are guide-ways 26 for the head 28 of a mandrel holder 29. The holder 29 has a longitudinal bore and groove 30 to receive the shank 31 of a tapering mandrel 32 and said mandrel is detachably held in the holder 29 by a set screw 33 or a fastening means which will permit of said mandrel 32 being removed and another size of mandrel substituted therefor. The mandrel, as best shown in Figs. 10 and 11 is oval in cross section, and has the top and bottom thereof provided with longitudinal grooves 34 and 35, the latter being dovetailed for a purpose that will hereinafter appear, under another caption.

The holder 29 has a bifurcated extension 36 resting upon an angle bracket 37 carried by the inner side of a pitman 38 slidable in a bearing 39 secured to the outer side of the end frame 2. The lower end of the pitman 38 has an inwardly projecting roller 40 extending into a cam groove 41 in the outer side of a cam 42 mounted upon a longitudi-

nally disposed drive shaft 43, journaled in the end frames 1 and 2. Loose on the shaft 43 and adapted, at predetermined times for rotative continuity therewith, is a large gear wheel 44 meshing with a small gear 70 wheel 45 on a driven shaft 46, journaled in the end frames 1 and 2, said shaft having an end thereof provided with a belt wheel 47 whereby the shaft can be driven from a suitable source of power. 75

With the extension 36 of the mandrel holder resting upon the bracket 37 of the pitman 38, it is apparent that the mandrel holder can be raised when the pitman 38 is raised through the medium of the cam 42, 80 and as the mandrel holder can descend by gravity and in synchronism with the pitman 38, it is possible to vertically reciprocate the mandrel and move the same to and from the dies 8 and 9. 85

Mandrel follower and its operating mechanism, (Figs. 1, 2, 3, 5, and 6.)—The confronting sides of the guides 5 and 6 are provided with vertical grooves 48 to receive bifurcated tongues 49 of a vertical reciprocable head 50. At the upper ends of the tongues 49 are barrels 51 for a longitudinally disposed rod 52, said rod having one end thereof mounted in the upper end of the pitman 38 and the opposite end thereof mounted in a pitman 53 slidable in a bearing 54, carried by the outer side of the end frame 1. The pitmen 38 and 53 are similar, the pitman 53 having the lower end thereof provided with a roller 55 extending into a cam 100 groove 56 in the outer side of a cam 57 mounted upon the end of the drive shaft 43, as best shown in Figs. 1 and 2. The cam grooves 41 and 56 are identical in contour and their purpose will be more fully understood in connection with a résumé of the general operation of the machine. 105

Loosely mounted in the lower bifurcated ends of the tongues 49 by bolts 58 and nuts 59 are the ends of a mandrel follower 60 adjustably held beneath the head 50. The follower 60 is adjusted by screw bolts 61 screwed into bosses 62 of the head 50, said screw bolts having the heads thereof loosely held in sockets 63 provided therefor in the upper edge of the follower. When the bolts 58 and nuts 59 are loose the follower 60 can be raised and lowered relatively to the head 50 and when properly adjusted the bolts 58 and nuts 59 can be tightened to firmly hold 110 the follower 60. In the initial formation of the blank the follower is adapted to co-operate with the mandrel 32 in shaping the blank, and then at a later period the follower is adapted to close a seam of a tube formed of 115 the blank. 120

Tube overlapping members and their actuating means, (Figs. 1, 3 and 4.)—At the ends of the dies 8 and 9, abutting the inner sides of the guides 5 and 6, are transverse 130

sets of sectional guides 64 providing angularly disposed guide grooves 65 coöperating with the upper beveled edges of the walls 7 of the bed plate 4 in supporting coöperating 5 lateral members 66 and 67 employed for overlapping the edges of the blank 19. The member 66 is adapted to move inwardly in advance of the member 67 and the member 66 has a concave edge 68 which provides 10 clearance for an edge of the blank operated upon by the flat beveled edge 69 of the member 67. The members 66 and 67 have the outer edges thereof adjustably connected to angle plates 70 provided with sets of aper- 15 tured ears 71. The apertured ears 71 are suitably connected by bolts 72 to the upper slotted ends of arms 73 and 74 fulcrumed upon longitudinally disposed rods 75 connecting the end frames 1 and 2. It is pref- 20 erable to use two sets of arms with the arms of each set opposing. The lower ends of the arms are bent outwardly and provided with transverse pins 76 and the ends of one pin are connected to the ends of the pin of the 25 opposing arm by coiled retractile springs 77 thereby providing means for holding the members 66 and 67 in retracted positions. The two sets of arms are identical in construction and considering the arms of one 30 set, the lower ends of the arms are provided with rollers 78 and 79, the roller 78 of the arm 74 being on a side opposite that of the roller 79 of the arm 73, whereby said rollers can be engaged by cams 80 and 81 mounted 35 upon the drive shaft 43. These cams are of such dimension that the member 66 will be actuated in advance of the member 67, although such movement is hardly perceptible during the operation of the machine.

40 *Tube ejector and its operating mechanism, (Figs. 1 and 4 to 7 inclusive.)*—In connection with the mandrel 32, it was mentioned that the groove 35 was dovetailed and the purpose of this groove is to hold a longitudinally reciprocable tube ejector 82 which has the bottom side thereof provided with a rack 83. This rack meshes with a pinion 84 mounted upon a shaft 85 journaled in the bifurcated extension 36 of the mandrel holder 29. One end of the shaft 85 has a beveled gear wheel 86 meshing with a horizontally disposed beveled gear wheel 87 mounted upon the upper end of a shaft 88 supported by a collar 89 on a depending bearing 90 of the holder 29. The lower end of the revoluble shaft 88 extends into a clutch barrel 91 and said clutch barrel is sleeved upon a shaft 92, journaled in bearings 93, carried by the outer side of the end 45 frame 2. The shaft 92, between the bearings 93, has a worm 94 meshing with a gear wheel 95 on the drive shaft 43. The shaft 92 has a fixed clutch member 96 adapted to be engaged by the clutch member 97 of the sleeve 91, and said sleeve is adapted to im-

part movement to the shaft 88 by virtue of a transverse pin 98 extending into longitudinal slots 99 in the clutch sleeve 91. The upper end of the clutch sleeve 91 is provided with a collar 100 and loosely engaging said collar is an arm 101 of a vertically disposed post 102 slidable in the bearing 39 of the end frame 2. The lower end of the post 102 has a roller 103 adapted to be engaged by a cam rib 104 on the periphery of the 75 cam 42, as best shown in Fig. 6. With the roller 103 in engagement with the cam rib 104 the clutch sleeve 91 is held in an elevated position and the clutch members 96 and 97 are separated, consequently the shafts 80 can be revolved independent of the shaft 88, thereby allowing the tube ejector to remain inactive during certain formative stages of a tube. Assuming however, that the clutch sleeve 91 is in a lowered position, the shafts 85 88 and 92 are driven in synchronism and the tube ejector 82 is shifted longitudinally of the mandrel 32. In order to provide clearance for a tube and the tube ejector 82, the pitmen 38 and 53 are provided with slots 90 105 and the guide 5 has an opening 106 longitudinally alining with the opening 25 in the guide 6.

So far means have been described for moving the ejector 82 whereby a tube on the 95 mandrel 32 can be ejected, and to restore the ejector 82 to a normal or retracted position, the outer end of the ejector 82 has an arm 107 slidable upon a rod 108, and between the mandrel holder 29 and the arm 107 is a 100 coiled compression spring 109 which is placed under tension when the ejector 82 is shifted to an extended position, and when the clutch members 96 and 97 are disconnected, the tension of the spring 109 is sufficient to withdraw the tube ejector 82 to a 105 retracted position.

Controlling mechanism of the machine and operation of producing a tube, (Figs. 1, 13 to 17 inclusive.)—Slidably keyed upon 110 the guide shaft 43 is the hub 110 of a clutch member 111 adapted to interlock with a clutch member 112 forming part of the large gear wheel 44, whereby said large gear wheel can be caused to impart a rotary 115 movement to the drive shaft 43. The hub 110 of the clutch member 111 has a circumferentially grooved collar 113 and loosely engaging said collar is a yoke 114 of a crank 115 loose upon a treadle shaft 116, journaled 120 in a bearing 117, carried by a plate 118 located at one side of the machine. The treadle shaft 116 has a treadle 119 and a crank 120. The crank 120 has a pivoted dog 121 adapted to engage a lug 122 of the 125 crank 115 and said dog is connected by a coiled retractile spring 123 to the crank 120 whereby said dog will be held in a position to engage the lug 122 when the same is encountered. The crank 120 is connected to 130

the plate 118 by a coiled retractile spring 124 and said crank is connected by another coiled spring 125 to the crank 115, the last mentioned spring being of less tension than 5 the spring 124.

The bearings 117 have an upright 126 and in said upright is a rock shaft having cranks 127 and 128, the former being connected to the upright by a coiled retractile 10 spring 129, and the latter being in the path of a cam 130 on the side of the clutch member 111. The crank 127 has the outer end thereof hook-shaped to engage a pin 131 carried by the side of the crank 115.

15 When the operator or attendant of the machine depresses the treadle 119, the shaft 116 is rocked and through the medium of the dog 121, the crank 115 is shifted to move the hub 110 of the clutch member 111 longitudinally of the drive shaft 43, thereby placing the clutch member in engagement with the clutch member 112 of the large gear wheel 44, causing rotative continuity of said large gear wheel and the driving 20 shaft. As the hub 110 of the clutch member 111 is carried with the drive shaft 43, the cam 130 is moved out of engagement with the crank 128, and the crank 127 engages the pin 131, locking the crank 115 25 whereby the clutch member 111 will be held in engagement with the clutch member 112. With the foot removed from the treadle 119, the coiled retractile spring 124 restores the treadle 116 and the crank 120 to normal position placing the spring 125 under additional tension to retract the crank 115, when 30 the crank 127 releases the pin 131. This is accomplished by the cam 130 of the clutch member 111 engaging the crank 128, elevating 35 the crank 127 and allowing the spring 125 to restore the crank 115 to normal position. As the crank 115 assumes a normal position the dog 121 automatically rides into engagement with the lug 122 and the 40 hub 110 is held in a retracted position, thereby disconnecting the clutch member and causing a cessation in the operation of the drive shaft 43.

Assuming that a blank has been placed 45 upon the dies 8 and 9, the treadle 119 depressed, the drive shaft 43 is driven and through the medium of the cams 42 and 57 the pitmen 38 and 53 are lowered, allowing the mandrel 32 to descend by gravity and 50 engage the blank. While the blank holds the mandrel, the mandrel follower 60 continues to descend and impinges the mandrel, as shown in Fig. 15, forcing the mandrel between the dies 8 and 9 and thereby bending 55 the blank to a channel form. The shape of the cam grooves 41 and 56 are such that the pitmen 38 and 53 are not raised high enough at the first lifting operation to raise the mandrel by engagement of the bracket 37 60 with the arm 36, consequently the mandrel 65

is only elevated, during the second lifting operation, when the bracket 37 of the pitman 38 picks up the mandrel holder 29 and both are farther elevated. As this operation takes place, the cams 80 and 81 actuate 70 the arms 73 and 74 and the members 66 and 67 thereof. As heretofore stated, the member 66 moves slightly in advance of the member 67, and as shown in Fig. 16, the member 66 bends one edge of the blank over on to the mandrel above the upper longitudinal groove 34 of said mandrel. The member 67 bends the other edge of the blank over on to the mandrel with said edge overlapping the other edge of the blank, and with these overlapping flanged edges over the upper groove 75 34 of the mandrel, the follower 60 descends and forces the flanged edges of the blank into the groove, thereby clenching the same with the bead of the seam within the groove 80 of the mandrel, thus providing a smooth periphery for the finished tube. During these operations the post 102 has been held in an elevated position by the cam rib 104, but as the mandrel follower is retracted, the post 102 is lowered thereby placing the 85 clutch members 96 and 97 in engagement and movement is imparted to the mandrel ejector 82 to force the finished tube off of the outer end of the mandrel. 90

The shape of the grooves in the large cams 42 and 57 at the ends of the drive shaft 43 and the position of the cams 80 and 81 of said shaft determine the relative coöperation of the mandrel, mandrel follower, tube 100 overlapping members and tube ejector, and I have found that perfectly tapered tubes can be expeditiously and economically produced with these coöperating devices and with one attendant at the machine. 105

What I claim is:—

1. A machine of the type described comprising dies, a mandrel adapted to press a blank between said dies to a channel form, lateral opposed members adapted to move one in advance of the other and bend the edges of a blank on said mandrel, said mandrel having a longitudinal groove therein, a mandrel follower adapted to engage the bent edges of the blank and force the same into the groove of said mandrel, and means actuated at each end of the machine for moving the mandrel follower and thereby the mandrel. 115

2. In a machine of the type described, 120 dies, a longitudinal grooved mandrel adapted to engage a blank on said dies and force said blank between said dies to a channel form, opposing members adapted to engage the edges of said blank and bend the same upon said mandrel, a mandrel follower adapted to force the edges of the blank in one of the grooves of said mandrel, means in the other groove of said mandrel adapted to eject a tube therefrom, and means actu- 125 130

- ated at each end of the machine for moving said mandrel follower and thereby the mandrel.
3. A tube forming machine adapted to 5 form a tapering tube from a blank, comprising a bed plate, dies on said bed plate a grooved tapering mandrel adapted to engage a blank on said dies, a mandrel follower adapted to engage said mandrel and force said blank and mandrel between said dies whereby said blank assumes a channel shape, members adapted to bend the edges of said blank on to said mandrel, and means in a groove of said mandrel adapted to eject 10 a tube therefrom.
4. A tube forming machine adapted to form a tapering tube from a blank, comprising dies, a mandrel adapted to descend by gravity and engage a blank on said dies, 15 a mandrel follower adapted to engage said mandrel and force said blank and mandrel between said dies whereby said blank assumes a channel shape, means adapted to raise and lower said follower, and means 20 adapted to bend the edges of said blank on said mandrel in position to be clenched by said mandrel follower.
5. In a machine for producing tapering tubes, dies adapted to support a blank in a 25 horizontal plane, a tapering mandrel normally held above said dies and adapted to descend by gravity on to a blank on said dies, a mandrel follower adapted to force said mandrel between said dies whereby the 30 blank is formed on said mandrel, and actuating means for said mandrel follower normally supporting said mandrel and movable independently thereof whereby said mandrel follower may recede after forcing said mandrel between said dies.
6. A tube forming machine adapted to 35 form a tapering tube from a blank having flanged edges, comprising dies, a grooved mandrel, a mandrel follower adapted to move said mandrel between said dies to impart a channel form to said blank, members movable one in advance of the other adapted to bend the edges of said blank over a groove of said mandrel, and cams adapted 40 to move said mandrel follower from said mandrel to provide clearance for the operation of said members and toward said mandrel after the bending operation of said members to 45 clenched the flanged edges of said blank in a groove of said mandrel.
7. A tube forming machine adapted to 50 form a tapering tube from a blank having flanged edges, comprising dies, a grooved mandrel, a mandrel follower adapted to move said mandrel between said dies to impart a channel form to said blank, movable members adapted to bend the edges of said blank over the groove of said mandrel, cams adapted to move said mandrel follower from 55 said mandrel to provide clearance for the 60 operation of said members and toward said mandrel after the bending operation of said members to clenched the flanged edges of said blank in a groove of said mandrel.
8. A tube forming machine adapted to 65 form a tube from a blank having flanged edges, comprising dies, a grooved mandrel, a mandrel follower adapted to move said mandrel between said dies to impart a channel form to said blank, members adapted to bend the edges of said blank over a groove of said mandrel, cams adapted to move said mandrel follower from said mandrel to provide clearance for the operation of said members and toward said mandrel after the bending operation of said members to 70 clenched the flanged edges of said blank in a groove of said mandrel.
9. In a tube forming machine embodying 75 dies, a mandrel adapted to descend by gravity on to a blank, a mandrel follower, follower moving means supporting said mandrel and adapted to release said mandrel and cause said follower to further move said mandrel between said dies whereby a 80 blank is shaped on said mandrel between said dies; a slideable ejector normally in one end of said mandrel and adapted to eject a tube therefrom, means actuated by said mandrel moving means adapted to move 85 said ejector in one direction, and means adapted to move said ejector in another direction.
10. In a tube forming machine embodying 90 dies, a mandrel, a mandrel follower, means actuated at each end of said machine for moving said mandrel and its follower whereby a blank is shaped on said mandrel between said dies; a slideable ejector normally in an end of said mandrel and adapted to eject a tube therefrom, means including a rack and pinion actuated by said mandrel moving means adapted to move said 95 ejector in one direction, and means independent of said mandrel moving means adapted to move said ejector in an opposite direction.
11. In a machine for producing tapered tubes, dies adapted to support a blank in a horizontal plane, a tapering mandrel nor- 100

mally held above said dies and adapted to descend by gravity on to a blank on said dies, a mandrel follower adapted to force said mandrel between said dies whereby the 5 blank is formed on said mandrel, actuating means for said mandrel follower normally supporting said mandrel and movable independently thereof whereby said mandrel follower may recede after forcing said mandrel between said dies, and members adapt- 10

ed to operate on the formed blank during an elevation of said mandrel follower independently of said mandrel.

In testimony whereof I affix my signature in presence of two witnesses.

WARREN W. STOLER.
